UNITED STATES PATENT OFFICE.

WINSLOW A. PARSONS, OF WELLESLEY, MASSACHUSETTS, ASSIGNOR TO RICHMOND
LACE WORKS, OF NEW YORK, N. Y., A CORPORATION OF MAINE.

DESIGN FOR LACE.

Application filed June 3, 1924. Serial No. 9,785. Term of patent 14 years.

To all whom it may concern:

Be it known that I, WINSLOW A. PARSONS, a citizen of the United States, residing at Wellesley, in the county of Norfolk and State of Massachusetts, have invented a new, original, and ornamental Design for Lace, of which the following is a specification, reference being had to the accompanying drawing, forming part thereof, wherein the single figure is a plan view of a piece of lace illustrating my new design.

I claim:

The ornamental design for lace as shown.
WINSLOW A. PARSONS.
